FOUNTAIN MOP

Filed May 3, 1930

INVENTOR

BY Ernest Edgar Allen

M. J. Graham
ATTORNEY

UNITED STATES PATENT OFFICE

ERNEST EDGAR ALLEN, OF SAN FRANCISCO, CALIFORNIA

FOUNTAIN MOP

Application filed May 3, 1930. Serial No. 449,463.

This invention relates to mops, and particularly to the type adapted to be irrigated or supplied with a supply of flowing liquid while the mop is in use. This type of mop is especially valuable for cleaning automobiles, bath tubs, hoppers, lavatory bowls and the like.

One of the objects of this invention is to provide a mop which may be irrigated while in use; other objects are to provide a handle for the mop which will support a hose or a liquid supply line; to provide means to maintain an end of a hose or a nozzle within the mop member of the mop; to provide in connection with the handle portion means to prevent the hose from being unintentionally released from the handle but to readily and easily be released or inserted, at the will of the operator; to provide such a structure which is simple, economical to manufacture, which requires no mechanical operation, and to generally improve upon devices of the character herein described.

With the above mentioned and other objects in view, the invention consists in the novel construction and combination of parts hereinafter described, illustrated in the accompanying drawing and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawing, wherein:

Figure 1 is a longitudinal side elevation.

Figure 2 is a longitudinal vertical cross section of Fig. 1, but showing hose nozzle without section.

Fig. 3 is a cross section on line 3—3 of Fig. 1.

Fig. 4 is a plan view showing preferred form of mop used.

Referring to the drawing, wherein like reference characters designate corresponding parts—1 is a mop portion of any suitable material, preferably absorbent, as cotton

strands forming a mop-like body mounted on a supporting member, which is here shown as a bar 2 of intertwined strands of wire, the fiber of the mop preferably being mounted on the bar by twisting the fibers between the 55 intertwined wire strands. The bar is bent upon itself to form a U-shaped structure at the portion mounting the mop as indicated by the cross section of the mop portion 3 in Figure 2. (See also Figure 4). This bar 60 member is preferably made of substantially rigid material, but may have a relatively small degree of spring action so as to relieve the pressure on the wrist of the operator while the mop is being used. 65

The prongs of the U-shaped member extend rearwardly from the mop portion to form the elongated substantially parallel prongs 4 upon which a hose carrying member 5 is mounted longitudinally of the elongated 70 prongs 4. The hose carrying member may be made of any suitable material, but in the preferred exemplification is made of sheet metal, and is also substantially U-shaped in transverse cross section, as best shown in Figure 3, and forms a handle portion for the brush (see Figure 1). The hose carrier may also be mounted longitudinally between the prongs 4 and parallel therewith, but for reasons hereafter set forth, I prefer to mount 80 it so that the channel through which the hose extends lies to one side only of the prongs. The member 5 is mounted on the elongated prongs 4 by forming the side edges thereof tightly around the prongs, as at 6, and the 85 mounting may be made more secure by impressing portions of said formed portions into the intertwined strands of wire, as by punchings 7. This structure gives a rigidity to that portion of the prongs 4 which are enclosed within the handle, where a degree of resiliency exists in the bar member 4 by reason of the material used therein.

The hose 8 which leads to a source of liquid supply, is passed through the hose carrier 5 95 from its rearward end 9 until the discharge end 10 lies within the absorbent mop portion 1, so that the mop portion may be irrigated and a constantly fresh supply of clean liquid may be supplied continuously to the mop 100

portion, and thereby the mop portion may be kept clean while the mop is being used for cleansing purposes, as well as furnishing a flushing fluid to carry away dirt or other matter from the surfaces being brushed or cleaned.

While the use of a nozzle on the hose is not essential to the proper and efficient use of the mop, I have in the drawing shown a nozzle 11 mounted on the discharge end of the hose, but the construction of the nozzle may be of any suitable type, and the particular construction thereof may be optional with the operator, but, for convenience, I prefer a nozzle having a shut off means whereby the liquid flow may be regulated at the mop. In forming the hose carrier member 5 around the prongs 4, I prefer to form them inwardly from the outside, as indicated at 12, Fig. 3, because this construction permits of greater space for the hose within the channel of the hose carrier 5, and prevents constriction of the hose by the walls of the carrier. This construction also provides for the prongs 4 to form a track on which the hose may rest and prevents the hose from slipping through the bottom opening of the U-shaped carrier (see Fig. 3).

Intermediate the mop 1 and the hose carrier 5 are mounted on the bar 2 resilient bumpers 13, which I prefer to mount on the bar by sliding the bar 2 through openings in the bumpers, as best shown in Fig. 1. These bumpers serve functions of supporting the forward end of the hose so as to hold the same more fixedly in place and act as a bumper to prevent the forward end of the hose carrier 5 from scratching or marring any polished surface, such as an automobile body, and the bumpers also serve to protect the fingers gripping the handle from being injured by rubbing or striking the surface being cleaned.

I have preferred to place my hose carrying member on one side only of the elongated prongs for the reason that it carries the hose into the mop on one side of the support member 2, and since there is usually a metal coupling member or a nozzle on the end of the hose, the danger of marring a polished surface by striking of metal thereagainst is practically eliminated.

Having thus described the invention what is claimed as new and desired to be protected by Letters Patent is:—

1. A fountain mop attachment for a hose, comprising a hand grip tubular body adapted to receive a length of hose and open longitudinally at one side providing a pair of spaced parallel terminal edges, a mop support member comprising elongated bars mounted along said terminal edges of the tubular body and extending beyond the end of the hand grip body portion, and a saturable member mounted on said extended portion,

said tubular portion of the hand grip being positioned on one side only of the said elongated bars.

2. A fountain mop attachment for a hose, comprising a hand grip tubular body adapted to receive a length of hose and open longitudinally at one side providing a pair of spaced parallel terminal edges, said body portion being arcuate in transverse cross section to fit a hose, a mop support member comprising elongated bars mounted along said terminal edges of the tubular body and extending beyond the end of the hand grip body portion, and a saturable member mounted on said extended portion, said tubular portion of the hand grip being positioned on one side only of the said elongated bars.

3. A fountain mop attachment for a hose, comprising a hand grip tubular body adapted to receive a length of hose and open longitudinally at one side providing a pair of spaced parallel terminal edges, said body portion being arcuate in transverse cross section to fit a hose, a mop support member comprising elongated bars mounted along said terminal edges of the tubular body and extending beyond the end of the hand grip body portion, and a saturable member mounted on said extended portion, the said terminal edges of the hose supporting body portion being bent inwardly upon itself providing within the transverse cross sectional area of the tubular body longitudinal channel portions adapted to receive the end portion of the elongated bars of the mop support member, whereby the tubular body is positioned on one side only of the mop support member.

In testimony whereof I affix my signature.

ERNEST EDGAR ALLEN.
